TYPEWRITER

Kelley D. Evans, Hamilton, Ohio, assignor of
one-half to C. E. Hooven, Hamilton, Ohio

Application September 20, 1937, Serial No. 164,729

7 Claims. (Cl. 197—17)

This invention relates to typewriters and particularly to typewriters wherein the type bars are swung to printing position by power driven means so that the printing impressions will be uniform and independent of pressure applied by the operator to the keys.

The object of the invention is to provide improved power-operated mechanism for actuating the type bars and for performing other functions, such as the carriage return, line and word spacing, and case shift, which is efficient in operation and has to a high degree the features of reliability and durability.

A further object is to accomplish the power-actuated movements through a power-operated actuator which is normally stationary but which is connected to the power source and actuated through selection by depression of the keys which are otherwise independent of the type bars.

The invention is applicable to or may be embodied in any standard form of typewriter or in connection with automatic typewriters, and in this respect the present invention is an improvement over my prior Patents Nos. 1,769,624, 1,769,625, and 1,769,626.

The invention may be briefly summarized as consisting in certain novel details of construction and combinations and arrangements of parts which will be described in the specification and set forth in the appended claims.

In the accompanying sheets of drawings in which I have shown an embodiment of the invention which operates with high efficiency,

Fig. 1 is a vertical sectional view of my improved typewriter taken substantially on the irregular line 1—1 of Fig. 2;

Fig. 2 is a rear view of the same;

Fig. 3 is a view partly in end elevation and partly in section viewing certain parts located beyond the section of Fig. 1;

Fig. 4 is a sectional view showing on an enlarged scale the mechanism at the lower right-hand portion of Fig. 1;

Fig. 5 is a sectional view substantially along the line 5—5 of Fig. 4;

Fig. 6 is a sectional view substantially along the line 6—6 of Fig. 5;

Fig. 7 is a sectional view showing the mechanism at the righthand corner of Fig. 1 on an enlarged scale, this view showing the key lever tilted forwardly to the position to which it is moved by the depression of one of the keys and showing the clutch controlling members in the positions that they occupy at the instant that

the clutch is engaged and ready to start the downward power stroke of the actuator;

Fig. 8 is a view similar to Fig. 7 showing the actuator at the bottom of its power stroke and showing how it moves one of the slide levers from the tilted position of Fig. 7 to its lowermost position;

Fig. 9 is a plan view with parts broken away showing the mechanism supported by the lower part of the frame or so-called sub-frame; and

Fig. 10 is a fragmentary plan view of the parts at the upper righthand corner of Fig. 2.

Referring now to the drawings, my improved typewriter includes a frame 10 at the front of which is a keyboard corresponding to the keyboard of an ordinary typewriter, several of the keys being shown at 11. The keys are mounted on key levers 12 which are pivoted on a cross rod 13 carried by a comb 14 which is mounted on a sub-frame 15 which, in this instance, is secured to the bottom of the frame 10 and supports a considerable portion of the power operated mechanism. This sub-frame, while in this instance is attached to and forms a support for the frame 10, may in practice be an integral part

of the frame 10. The key levers 12 are extended downwardly, as shown at 12a, below the rod 13 on which they are pivoted, and at their lower ends are extended inwardly as shown at 12b.

The inward extensions 12b bear against the forward edges of the slide levers 16 each of which is individual to one of the keys of the keyboard and is adapted to be swung inwardly when the key is depressed and then to be slid downwardly by the action of the power-driven actuator, as

will be explained subsequently. The upper ends of these slide levers 16 are slotted, the slots receiving a fulcrum wire 17 extending across the slots of a comb 18 which guides the upper ends of the slide levers. The lower ends of the slide

levers are provided with forward extensions 16a which slide in the slots of a lower comb 19, both the combs 18 and 19 as well as the comb 14 being supported by the sub-frame. The slide levers are normally held in the vertical position shown

in Fig. 1 by springs 20 which extend upwardly and forwardly from the ends of the extensions 16a to a spring bar 20a secured to the lower part of comb 14. Beneath the lower ends of the slide levers 16 is a locking bar 21 the function of which

will be explained presently.

The slide levers have rearward extensions 16b which are connected by adjustable links 22 to levers 23 which at their rear ends are pivoted on a fulcrum wire 24 like the key levers of an

typewriter. The rear ends of the levers 23 are connected by a link 25 to a lever 26 which is pivoted on a fulcrum wire 27 and is connected by a link 28 to a lever 29 which is pivoted on a fulcrum wire 30.

The lever 29 is connected by a link 31 to a lever 32 which is pivoted on a fulcrum wire 33 and is connected by a link 34 to a lever 35 which is pivoted on a fulcrum wire 36.

The lever 35 is connected by a link 37 to a lever 38 which is pivoted on a fulcrum wire 39 and is connected by a link 40 to a lever 41 which is pivoted on a fulcrum wire 42.

The lever 41 is connected by a link 43 to a lever 44 which is pivoted on a fulcrum wire 45 and is connected by a link 46 to a lever 47 which is pivoted on a fulcrum wire 48.

The lever 47 is connected by a link 49 to a lever 50 which is pivoted on a fulcrum wire 51 and is connected by a link 52 to a lever 53 which is pivoted on a fulcrum wire 54.

ordinary typewriter. In this instance, the levers 23 terminate at their forward ends a short distance inwardly of the fulcrum wire 13 of the key levers 12 and their forward ends are guided in the slots of an ordinary typewriter front comb 25. The levers 23 are connected to and operate type bars 26 in the same manner as in an ordinary typewriter through the medium of sub-levers 27 which are fulcrumed on a rod 28 extending across the main frame 10 and at their lower ends have pin and slot connections 29 with the levers 23, while at their upper ends they have pin and slot connections with rearward extensions 26a of the type bars. The latter in turn are mounted to swing in the usual manner in the slots of a segment 30 and are mounted on the usual fulcrum wire carried thereby. It will be understood that the type bars are not only mounted in the customary manner but, as in the ordinary typewriter, when swung to printing position enter the usual guide indicated at 31. The segment 30 receives on its rear side the usual universal bar 32 which functions in the customary manner to operate the escapement for spacing the carriage through the usual or any suitable escapement mechanism which I have not here illustrated. I have shown the platen in conventional manner at 33 and also portions of the carriage frame at 34 and a portion of the carriage at 35.

It was previously mentioned that the slide levers 16 are connected to the levers 23 by adjustable links 22. While these adjustable links may be formed in different ways, in this instance the links are each composed of two parts including an upper part 22a hooked onto the lever 23 and provided with a threaded lower part screwed into a sleeve-like member 22b the lower part of which is slotted to receive the rearward extension 16b of one of the slide levers 16. By adjusting the links 22 the density of the printed impression may be varied.

It is to be noted that the key levers 12 have no direct mechanical connection with the levers 23 and therefore with the type bars 26, and, as will presently appear, the type bars are swung to printing position by a power driven actuator the movement of which is initiated and which is caused to function to swing to printing position the type bar corresponding to one of the keys of the keyboard when the key is depressed by the operator.

For the purpose of actuating the slide levers 16 and the levers 23 corresponding to all the type bars as well as the slide levers for other special functions to be referred to, I employ a power driven actuator 36 in the form of a bar extending crosswise of the sub-frame 15 and mounted upon arms 37 of a rock shaft 38 which is journaled in the sides of the sub-frame 15. This actuator, in contradistinction to the actuator of my prior patents referred to, is normally stationary and is adapted to swing through an arc, which is substantially vertical, from the normally stationary position shown in Fig. 4 to a lowermost position shown in Fig. 8, and then return to its former position until the next cycle is initiated. The power movement is started by the depression of any one of the keys, which results in the swinging of the corresponding slide lever 16 to the position shown in Fig. 7 so as to bring a shoulder 16c on the lower part of the slide lever underneath the actuator 36, each of the slide levers being provided with one of these shoulders so that when any one of them is swung inwardly by the depression of the corresponding key, the shoulder

will be moved under the actuator, and, when the latter is swung downwardly, the slide lever will be pulled downwardly so as to actuate the corresponding lever 23 and type bar 26 or other parts which are to be power-actuated.

I will next describe the mechanism by which the actuator is shifted and its movements controlled. I prefer to employ as a source of power an electric motor 39 which in this instance is mounted on the rear of the sub-frame 15, the shaft of this motor being provided with two pulleys which drive two belts 40 and 41 the former of which is utilized to impart movements to the actuator and the latter for line spacing and carriage return. The belts 40 and 41 run continuously so long as the motor is in operation, the belt 40 extending from the pulley on the motor shaft forwardly and around a normally loose pulley 42 of a clutch which is designated as a whole by the reference character 43. The pulley 42 normally runs loosely on an inner hub 44 which is mounted on a shaft 45 supported in bearings 46 on the lower part of the sub-frame and provided at one end with a crank disk 47 which is connected by a link 48 to an arm 49 fixed to the rock shaft 38. In this instance the pulley 42 is adapted to engage and to be disengaged from the hub 44 by a roller 50 which is adapted to move in a tapered notch 51 formed in the periphery of the hub 44 being acted upon by one or more springs 52 located in recesses of the hub so that when the roller is released they will move the roller into the narrower part of the notch and thus cause the clutch to be engaged. The roller projects beyond opposite faces of the hub 44 and is provided at both ends with buttons 53 (Fig. 5) which are adapted to be engaged by the fingers of a clutch yoke 54 and held by the latter so as to normally keep the roller in the relatively wide part of the notch. The clutch 40 yoke is supported by a cross-member in the lower part of the sub-frame 15, and it is provided with a forwardly extending arm 55. The yoke 54 is normally maintained in clutch disengaging position by a spring 56. When it is in this position, its forward end which is on a bevel is engaged by a pin 57 (Fig. 4) on a pawl 58 normally pressed by a spring 59 against a pin 60 carried by a pawl lever 61 which is connected by a link 62 to a universal trip bar 63 which extends across the lower rear ends of the slide levers 16 and is attached at its ends to upstanding arms 64 pivoted on the sides of the sub-frame 15. A spring 65 normally presses the universal trip bar 63 against the lower ends of the slide levers 16 in the manner shown in Fig. 4.

The arrangement is such that when any one of the keys is depressed the lower end of the corresponding key lever 12 is swung inwardly rocking the corresponding slide lever inwardly about the fulcrum wire 17 to the position shown in Fig. 7. This simultaneously accomplishes two things—it moves the shoulder 16c under the actuator 36 and it swings the universal trip bar 63 rearwardly to the position shown in Fig. 7 so that the link 62 will rock the lever 61 and cause the pin 57 on the pawl 58 to be pressed against the beveled end of arm 55 and thus rock the arm and the clutch yoke 54 about their pivotal axis, causing the arms of the yoke to move under the buttons 53, thus releasing the roller 50 and allowing the clutch to become engaged by reason of the fact that the springs 52 move the roller 50 forwardly into the narrower part of the notch 51 so as to cause the rotating pulley 42 to be temporarily gripped to

the hub 44. The clutch makes one complete revolution and is then disengaged, and during this revolution the actuator has been swung downward or given its power stroke which moves the 5 slide lever downwardly and then is returned and stops at its uppermost position shown in Fig. 4. The disengagement of the clutch after the hub 44 has been given one revolution is accomplished by reason of the fact that when the pin 57 elevates the forward end of the arm 55 so as to rock 10 the rear end of the yoke 54 downwardly and thereby release the buttons 53 and roller 50, the pin 57 rides under the point at the lower side of the beveled end of the arm 55, thus permitting the 15 clutch yoke 54 to immediately rock back to its previous position such that it will again reengage the buttons 53 on the completion of the revolution of the hub and again disengage the clutch. The spring 56 returns the clutch yoke to its previous 20 position to again disengage the clutch and at the same time the spring 65 returns the universal trip bar to its former position shown in Fig. 4, the spring 20 meanwhile having disengaged the shoulder 16c from the under side of the actuator and returned the slide lever to its former 25 position. It was previously mentioned that a locking bar 21 is provided beneath the lower ends of the slide levers. It will be observed that when the slide levers are moved 30 downwardly by the actuator from the position shown in Fig. 7, the lower ends of the slide levers pass below the top of the locking bar 21 and, in fact, engage the rear surface thereof, as shown in Fig. 8. Accordingly, this locking bar prevents 35 the shoulder 16c of the slide lever from sliding beneath the actuator until after the power stroke of the actuator is completed. On the return stroke of the actuator, the slide lever is pulled upwardly and restored to its previous position 40 by the associated spring 20, and in so doing the slide lever is pulled upwardly so that the lower end thereof is over the top surface of the locking bar, as shown in Fig. 1.

It was previously stated that as soon as the 45 clutch yoke is rocked so as to cause the clutch to be engaged by the pin 57 passing under the point at the lower end of the bevel of the arm 55, the clutch is engaged and immediately thereafter the clutch yoke comes back to its former position, i. e., to the position to again disengage the 50 clutch when the hub has made one revolution. On the return of the universal trip bar 63 to its former position, it restores the link 62 and lever 61 to their former positions, and in doing so the 55 pin 57 does not again rock the clutch yoke but yields and passes back under the point and again is restored against the beveled end of arm 55. On the return movement of the trip bar and consequently on the return movement of the pin 57, the latter does not again rock the yoke 54 to clutch engaging position for the reason that the pin 57 is on the spring-pressed pawl 58 and during its return movement the spring yields and allows the pin 57 to pass under the beveled 60 end of arm 55.

At this point I wish to call attention to the fact that since the clutch yoke is restored to its clutch disengaging position immediately after the clutch is engaged in the manner just stated, the clutch will be engaged only during one revolution and is then disengaged regardless of whether the operator quickly releases the key or keeps it depressed for a time.

Thus, as the operator depresses the various keys 75 corresponding to the printing characters, the

typewriting is accomplished by the type bars being swung to printing position through the action of the actuator which functions in the manner above explained each time that one of the keys is depressed. It will be understood that as 5 the type bar is swung to printing position it actuates the universal bar which actuates the escapement to accomplish the letter spacing. For word spacing, I employ the usual spacer bar 66 (Fig. 1) mounted on two levers 67 at opposite 10 ends of the keyboard and fixed to a shaft 68 to which is attached a downwardly and rearwardly extending arm 69 the lower end of which engages one of the slide levers 16 the same as the lower 15 ends of the key levers 12. The slide lever associated with the arm 69 functions the same as the slide levers associated with the keys of the keyboard, but in this instance it is connected by one of the adjustable links to an arm 70 (Fig. 1) fixed to a cross shaft 71 to which is attached a 20 rearwardly and upwardly extending arm 72 connected by a lever 73 which in turn is connected to a rearward extension of the universal bar 32. Thus, when the space bar 66 is depressed by the 25 operator, the actuator 36 functions to actuate the universal bar 32 so as to accomplish the word spacing but without moving a type bar as is the case when any of the keys corresponding to the printing characters are depressed.

As is well known, it is customary to case-shift, 30 i. e., to shift from the lower case letters to the upper case and vice versa either by changing the position of the platen or by changing the position of the segment to which the type bars are connected, and, in the ordinary typewriter, the 35 case-shift is accomplished by a shift key. I provide a shift key in the keyboard but in this instance the case-shift is accomplished by the movement of the actuator the same as when the typewriting is done by pressing the character keys. I provide 40 for this purpose a shift key which is designated 11a in Fig. 3. This shift key is connected to a key lever 12c which is mounted on the fulcrum wire 13 the same as the key levers 12. This key lever 12c has a downward extension and is associated 45 with one of the slide levers 16 similar in all respects to the slide levers associated with the character keys. However, in this instance the slide lever, as shown in Fig. 3, is connected by one of the adjustable links 22 to a lever 74 which is mounted on the fulcrum wire 24 on which 50 the levers 23 are fulcrumed. This lever 74 has an upward extension 74a which effects the shifting either by shifting the platen or by shifting the segment, but in this instance the platen, the upward extension 74a engaging the rear side of 55 the lift frame 75 and this in turn lifting the platen upon the actuation of the lever 74 by the actuator. As is customary in typewriters where-in the shift is accomplished by shifting the platen, 60 the lift frame 75 has a lift rail 76 which is engaged by a roller 77 of the carriage a portion of which is shown at 78. In this same figure as well as in Fig. 1 are shown the way rod 79 and the front rod 80 on which the carriage frame is 65 supported and slides. As is customary when the shift is made for upper case letters, the platen or segment remains in its shifted position until the shift lock release key is depressed. I contemplate using the ordinary shift lock release key 70 which functions in the customary manner.

Thus it will be seen that by depressing the character keys the typewriting is accomplished by the actuator accompanied by the usual letter spacing, and that the word spacing is accom- 75

plished by the actuator by the depression of the space bar, and the shift also is accomplished through the actuator by the depression of a special shift key.

5 It was previously stated that the carriage return and the line spacing are accomplished by power-actuated mechanism, and this mechanism is illustrated and will now be described although this particular part of the typewriter is claimed in a 10 companion application Serial No. 164,370 filed of even date herewith.

For the carriage return and line spacing operations I employ the same motor 39 as is used in swinging the type bars to printing position and for the case shift and word spacing. The motor shaft, as previously stated, drives not only the belt 40 but also the belt 41. The latter belt rotates a pulley on a short shaft 82 mounted on the rear of the sub-frame. This shaft 82 is connected by suitable reduction gearing, in this instance worm gearing 83, to a vertical shaft 84 supported at the rear of the machine and extending upwardly to the upper rear portion thereof where it is designed to act as a drive for a special 25 clutch which when engaged by the depression of a key line-spaces and returns the carriage.

To effect the line spacing and carriage return operations, I utilize a rail 85 supported at its ends in brackets 86 mounted at opposite ends of the rear corners of the carriage frame 34, as best shown in Fig. 2. This rail is not fixed to the brackets 86 but has a limited endwise movement therein by reason of a pin and slot connection indicated at 87 with each of the brackets 86. The rail 85 is of course normally stationary but is adapted to be moved endwise first relative to and then with the carriage frame by being pinched between two rollers 88 and 89 at least the peripheries of which are preferably of soft 30 rubber. The roller 88 is fixed to the upper end of the vertical shaft 84 which rotates constantly so long as the motor 39 is operated. The roller 89 is mounted for rocking movement toward and from the roller 88 on a short lever 90 pivoted at 35 81 on a bracket 92 which supports the upper end of shaft 84, the bracket 92 being secured to the rear central portion of the main frame 10, as clearly shown in Fig. 2. Rotary motion is transmitted from the shaft 84 to the roller 89 by two 40 gears consisting of a gear 93 fixed to the shaft 84 just beneath the roller 88 and a gear 94 carried by the lever 90 just beneath the roller 89. The gear 94 and the roller 89 are on a short stud 45 and rotate together on the lever 90.

When the parts are in the position shown in 50 Fig. 1, the roller 89 is not in driving relation with the rail 85 but nevertheless the gears are sufficiently in mesh so that both the gear 94 and the roller 89 are normally rotated idly. The 55 lever 90 is adapted to be swung from the disengaged position shown in Fig. 1 to the engaged position in operative relation to the rail 85 by a toggle consisting of two links 95 and 96 one connected to a depending portion of the bracket 60 92 and the other connected to the lower end of the lever 90, as clearly shown in Fig. 1. As the 65 toggle is straightened, and in practice moved upwardly slightly past the center, the lever 90 is swung to vertical position bringing the gears into full mesh and swinging the roller 89 against the rail 85 which is then pinched sufficiently 70 tightly between the two rollers to cause it to move endwise, as will be explained. The toggle is adapted to be straightened so as to bring the 75 gears 93 and 94 into full mesh and the rollers

into driving relation with the rail 85 so as to effect first the line spacing movement of the platen and then the return of the carriage by the power mechanism including the power driven actuator 36 previously described. This operation 5 is initiated by the depression of a special key of the keyboard which in precisely the same manner as before rocks one of the slide levers 16, resulting as before in the tripping of the clutch followed by the downward power stroke of the actuator. The particular slide lever thus actuated, instead of operating one of the levers 23, rocks a bell crank 97 pivotally mounted at 98 on the sub-frame (see particularly Fig. 1). The end of one of the arms of the bell crank 97 is located beneath the extension 16b of the slide lever in question, and when the slide lever is depressed by the actuator, the other arm of the bell crank moves rearwardly a rod 99 which is connected to an arm 100 on a rock shaft 100a, 20 the latter having a second arm 100b (Figs. 1 and 9) which is connected to and adapted to shift a vertical rod 101 connected to the toggle arms 95 and 96.

By the depression of one of the keys by the 25 operator, the rollers 88 and 89 are thus brought into driving relation with the rail 85 which is moved in an endwise direction. By reason of the pin and slot connection between the rail 85 and the carriage frame, the rail first moves relative to the carriage frame substantially the 30 length of the slots of the pin and slot connection between the rail and the brackets 86. In order that this movement may be effective to turn the platen for the line spacing, I attach to the righthand end of the rail as the same is viewed in Fig. 2 an arm 102 which is journaled in a bracket 103 forming an extension of the adjacent bracket 86. This arm 102 is on a rock shaft 104 in the form of an upstanding barrel 40 which is journaled to the end of the bracket 103 and has at its upper end an arm 105 which is connected by a link 106 (see Figs. 1 and 10) to the ordinary line space plunger 107 (Fig. 1) which carries a pawl 108 adapted to engage a 45 ratchet 109 on the end of the platen shaft. This plunger 107 is adapted to be operated in the usual manner by the line space lever at the front corner of the main frame and is not here shown.

As soon as the short movement of the rail 50 relative to the carriage frame is completed and the line spacing accomplished, as just stated, the pins reach the ends of the slots, whereupon the further endwise movement of the rail 85 causes the carriage return. When the return movement is completed, a projection 110 (Fig. 2) engages an adjustable stop indicated at 111 in Fig. 2 on the front rod 80. The front rod is normally fixed in the typewriter frame, but, in accordance with the present invention, has a special mounting which permits it to have a slight endwise movement when the adjustable stop 111 is engaged by the projection 110 of the carriage frame which movement is opposed by the action of a spring 113, in this instance at the lefthand end 60 of the rod when viewed from the front of the typewriter. The purpose of this endwise movement of the front rod 80 is to break the toggle composed of the links 95 and 96 and disengage the clutch composed of the rollers 88 and 89 in 65 so far as their driving relationship with the rail 85 is concerned. To accomplish this, I mount on a bracket 114 secured to the righthand end of the main frame 10 a bell crank 115 the upper end of one of the arms of which is in line with 70

the front rod 80 while the other arm extends inwardly substantially horizontally and is connected to the upper end of a substantially vertical rod 116 the lower portion of which passes 5 through the horizontal arm of the bell crank 97 which was previously lowered by the actuator and the slide lever to initiate the carriage return. At the lower end of the rod 116 is a shoulder preferably in the form of an adjustable nut so arranged that when the carriage return 10 is completed, causing the endwise movement of the front rod 80, the rocking of the bell crank 115 and the upward movement of the rod 116 restores the bell crank 97 to its previous position, breaking the toggle composed of the links 15 95 and 96 so as to swing the roller 89 to the position shown in Fig. 1 and stop the driving action on the rail.

The depression of the carriage return key results in the line spacing movement given to the platen followed by the return of the carriage, and these two operations are accomplished one after the other when the carriage is at any position other than at its righthand position. However, the mechanism which I have provided admits of further line spacing when the carriage is at its righthand position by the further depression of the carriage return key, that is to say, after the carriage is returned the operator 25 can give as many additional space movements to the platen as desired by depressing the carriage return key one or more times. These spacing movements are imparted to the platen by the power mechanism, but since the carriage is 30 now in its righthand position, the effect of depressing the key is simply to cause the power mechanism to straighten the toggle which moves the rail to the extent permitted by the pin and slot supporting connections for the rail 85, resulting in the line space movements only. It might be mentioned at this point that upon the breaking of the toggle and the spreading of the rollers 88, 89 the rail 85 moves to the right a distance permitted by the length of the slots. This 35 return movement is caused by the spring 107a which is connected to and normally returns the line space plunger 107 to its normal position. This return of the rail 85 makes it possible to impart subsequent line spacing movements by the depression of the carriage return key after the carriage has returned to its right-hand position. It might be stated at this point also that the spring 113 cushions the blow when the carriage reaches its return position and it serves 40 also to give a slight forward movement to the carriage after its return movement is completed, resulting in a slight return movement of the bell crank 115 and a downward movement of the rod 116 (by its own weight), thus lowering it to the position shown in Fig. 1 and permitting subsequent operation whether simply for line spacing purposes or for both line spacing and carriage return.

In concluding the description of this part of the mechanism, it might be stated that because the mechanism by which the line spacing is accomplished through the actuation of the power mechanism is connected to the ordinary line space plunger, it is possible for the operator to 45 effect line spacing in the usual manner by operating the customary line space lever.

The operation is as follows: When the operator is ready to do typewriting with the improved typewriter described above, the motor 39 is started by closing a conveniently located switch. The

operator will then do the typewriting by operating the keys as in an ordinary typewriter. Each time that a key is depressed the associated slide lever is swung rearwardly, causing the universal trip bar to be swung rearwardly, resulting in the engagement of the clutch which then makes one revolution and is again disengaged, the actuator meanwhile having been given its power stroke and returned to its previous position. This movement of the actuator in the manner already 10 explained moves the type bar to printing position which is followed by the letter spacing through the usual escapement mechanism. It might be here stated that each cycle of movement of the clutch and the clutch controlling parts and of the actuator is completed in a sufficiently short space of time that the machine is capable of being operated by the most rapid typist.

The word spacing is accomplished by the depression of the space bar which tilts one of the slide levers and causes the actuator to move the universal bar in the same manner as it is moved for letter spacing.

When the line is completed, the operator depresses the carriage return key and this results in the closing of the toggle composed of the links 95 and 96 and the movement of the rail 85 to first impart a line spacing movement to the platen and then return the carriage to its righthand position until the adjustable stop is reached, whereupon the front rod 80 is moved endwise sufficiently to operate the bell crank and linkage which again breaks the toggle. With the carriage in its righthand position, as many additional line spacing movements may be imparted to the platen as desired each being power-operated in the manner previously explained.

When the operator desires to make a case shift, the shift key is depressed, whereupon the shift is accomplished by the power mechanism either by changing the position of the platen or changing the position of the type bar segment.

Thus it will be seen that the operator has simply to touch lightly the various keys and the space bar to perform all of the functions necessary for typewriting purposes, resulting in the typewritten matter being of uniform appearance throughout and of course reducing materially the muscular effort and manual movements necessary to cause the various functions or operations to be performed under the power of the motor. The movement of the carriage for tabulating and indenting purposes and the manipulation of the ribbon are preferably accomplished manually as in the ordinary typewriter, all other operations, however, being effected by the power mechanism controlled or initiated by the slight movement of the keys or the space bar.

While I have shown the preferred construction, I do not desire to be confined to the precise details of arrangement or construction but aim in my claims to cover all modifications which do not involve a departure from the spirit and scope of the invention.

Having thus described my invention, I claim:

1. In a typewriter, a frame, a keyboard, type bars, power means for swinging the type bars to printing position including a normally stationary actuator, a normally disengaged clutch, members associated with the keys and connected with the type bars and adapted to be shifted to a position to be engaged by the actuator, and means operated by any of said members on the

depression of the corresponding keys for tripping said clutch.

2. In a typewriter, a frame, a keyboard, type bars, power means for actuating the type bars comprising a normally stationary actuator, a normally disengaged clutch, members associated with the keys and mechanically connected to the type bars, said members being adapted to be shifted by the depression of the associated keys to a position to be engaged by the actuator, and a clutch tripping member adapted to be shifted by the movement of any of said members following the depression of the corresponding keys.
3. In a typewriter, a frame, a keyboard, a normally stationary intermittently movable actuator for swinging the type bars to printing position, means adapted to be actuated by the depression of the keys for establishing connection between the actuator and the type bars, power means including a normally disengaged clutch for operating the actuator, and means operated by said first named means for causing the clutch to be engaged and then disengaged after one revolution.
4. In a typewriter, a frame, a keyboard, type bars, a power driven actuator for swinging the type bars to printing position, members connected to the type bars and associated with the different keys of the keyboard, means including a normally disengaged clutch for swinging the actuator, and a trip bar for controlling said clutch and adapted to be actuated by any of said members.
5. In a typewriter, a frame, a keyboard, type bars, slide levers associated with the keys of the keyboard and mechanically connected to the type bars, an intermittently movable actuator for giving sliding movements to said slide levers,

means operated by depression of the keys of the keyboard for giving said slide levers tilting movements to a position to be engaged by the actuator, power means for imparting operative movements to said actuator and including a normally disengaged clutch, and means operated by said tilting movements of the slide levers for controlling the clutch.

6. In a typewriter, a frame, a keyboard, type bars, slide levers associated with the keys of the keyboard and mechanically connected to the type bars, an intermittently movable actuator for giving sliding movements to said slide levers, means operated by depression of the keys of the keyboard for giving said slide levers tilting movements to a position to be engaged by the actuator, power means for imparting operative movements to said actuator and including a normally disengaged clutch, and means operated by said tilting movements of the slide levers for controlling the clutch, the connection between each type bar and its associated slide lever including adjustable means by which the type impression may be varied.

7. In a typewriter, a frame, a keyboard, type bars, slide levers associated with the keys of the keyboard and mechanically connected to the type bars, an intermittently movable actuator for giving sliding movements to said slide levers, means operated by depression of the keys of the keyboard for giving said slide levers tilting movements to a position to be engaged by the actuator, power means for imparting operative movements to said actuator and including a normally disengaged clutch, and a trip bar for the clutch adjacent said slide levers and arranged to be shifted by said tilting movements thereof.

KELLEY D. EVANS.
